OZONIZER

Filed Jan. 30, 1928

UNITED STATES PATENT OFFICE

ALBERT E. EVANS, OF CLEVELAND, OHIO, ASSIGNOR, BY MESNE ASSIGNMENTS, TO THE COROZONE COMPANY, OF WILMINGTON, DELAWARE, A CORPORATION OF DELAWARE

OZONIZER

Application filed January 30, 1928. Serial No. 250,604.

This invention relates to ozonizers and has for its object the provision of a simple, inexpensive, quiet and practical electric device whereby ozone can be produced cheaply and 5 reliably for purifying, disinfecting and deodorizing purposes in the toilet and sanitary rooms of hotels, office buildings, railway stations, steamships, public halls, theatres, and other places.

10 In the drawings accompanying and forming a part of this application I have shown one physical structure in which my invention is embodied, although it will be understood that these drawings are intended to be illustrative of principles rather than exhaustive of the appliances by which the same can be utilized.

Fig. 1 is a vertical sectional view through a specimen ozonizer in place on a wall, corresponding to the line 1—1 in Fig. 2; Fig. 20 2 is a horizontal sectional view on the line 2—2 of Fig. 1; Fig. 3 is a perspective view of the apparatus showing the parts separated; and Fig. 4 is a diagram of the magnetic and 15 25 electric connections.

In its preferred form the casing of my improved ozonizer consists of a rectangular sheet metal box having a back 1 adapted to be secured in vertical position to a wall, a front 30 2 spaced therefrom, and vertical sides 3—3, here shown as outwardly-displaced at 4—4 to define inwardly-opening recesses for a purpose hereinafter explained. The inner faces of the walls 1 and 2 are here shown as covered by insulating layers 5 of any suitable material such as waxed paper.

Located inside this casing with its edges tightly received in the recesses 4—4 is the rectangular laminated frame 6 of a transformer, said frame having two vertically-spaced, horizontal portions 7 and 8, the former having a primary coil 9 wound thereon and the latter a secondary coil 10. In the present embodiment the coil 10 is made with approximately 45 ten times the number of turns as the primary 9 so as to increase the voltage from 110 volts to upwards of ten thousand volts. In addition to the cross members 7 and 8 of the transformer frame I have also shown a third, narrower cross member 12 for the purpose of se-

curing a small amount of magnetic leakage at all times, regardless of the demagnetizing effect of the winding 10, and thereby inducing a more powerful magnetism in the core frame.

The coils 9 and 10 are both spaced from the rear wall 1 of the casing and between said coils and said rear wall I interpose a narrow, flat-sided, elongated tube 13 of suitable insulating material such as mica wound in layers and suitably cemented together. The upper and lower ends of this tube or flue are left open to enable the circulation of air and have free communication with suitable inlet apertures 14 in the bottom plate 15, and with a suitable screen-cloth-covered outlet opening 16 in the top plate 17, with which said casing is provided. Inside said tube I locate a rough surfaced sheet 18 of metal, so located relatively to the wall of the tube as 20 to define therewith a passage-way for air. One terminal 19 of the secondary winding is connected to said sheet of metal, the wall of the tube being preferably slotted as shown at 25 to enable the ready introduction and removal of the electrode. The other terminal 21 of the secondary winding is suitably grounded to the plate 1 of the casing, or other member electrically connected therewith. In 30 the present embodiment this is effected by 20 welding the terminal 21 to the frame. 75

The electrode 18 is preferably made of some oxidation-resisting metal such as aluminum and to secure the roughness desirable I have found nothing better than a 35 piece of woven-wire-screen-cloth of this material. Other metals like brass, copper, iron, etc. can be employed, but these ordinarily become wasted away by the operation of the device, and frequently produce an acrid and unpleasant odor, from which aluminum and certain other of the oxidation-resistant metals are free.

Alternating current at 110 volts is supplied to the primary coil by way of the terminal wires 22. The essential electric and magnetic connections are illustrated in Figure 4. The screen cloth member 18 constitutes one electrode and the casing and its internal metal parts constitute the other electrode. Upon

energizing the transformer the surface of the electrode 18 becomes bathed with a dim, purplish-colored light which is apparently of the nature of the so-called "corona discharge" since it is quiet and noiseless. Thermal circulation of the air through the tube 13 past this electrode causes the same to become sufficiently ozonized for the disinfecting and deodorizing purposes hereinbefore mentioned.

10 The cost of the apparatus is very small, its consumption of current is only nominal, the sanitary, therapeutic, germicidal, and deodorizing effect of ozone is much superior to that of the oils and other chemical preparations customarily employed for these purposes, and the device requires no refilling, renewal, or attention.

It will be understood, however, that while I have described in detail the particular physical embodiment of my invention herein chosen for purposes of illustration, I do not limit myself to those details or to that physical embodiment in any wise except as specifically recited in my several claims which I desire may be constructed each independently of limitations contained in other claims.

Having thus described my invention what I claim is:

1. An ozone machine comprising: a casing; a transformer located in said casing with one side thereof slightly spaced from the corresponding wall of said casing; a flat tube of insulating material interposed between said side and said wall and open at its ends to permit the passage of a current of air therethrough; an electrode disposed in said tube; and connections connecting said electrode to a secondary terminal of said transformer.

2. An ozone machine comprising: a casing, having longitudinal grooves on the interior of two opposite walls; a transformer located in said casing with the two edges of its core tightly received within said grooves and with one side thereof slightly spaced from another wall of said casing; a flat tube of insulating material interposed between said side and said other wall and open at its ends to permit the passage of a current of air therethrough; an electrode disposed in said tube; and connections connecting said electrode to a secondary terminal of said transformer.

3. An ozone machine comprising: a casing, acting as an electrode; a transformer located in said casing; an electrode disposed within said casing; insulating material interposed between said electrode and said casing; and connections connecting said casing and said electrode to the secondary terminals of said transformer.

4. An ozone machine comprising: a casing, acting as an electrode; a transformer located in said casing, and having its core tightly in electrical contact with said casing; an electrode disposed within said casing; insulat-

ing material interposed between said casing and said core on the one hand and said electrode on the other hand; and connections connecting said core and said electrode to the secondary terminals of said transformer. 70

5. An ozone machine comprising: a casing, having longitudinal grooves on the interior of two opposite walls, and acting as an electrode; a transformer located in said casing and having the two edges of its core tightly received within said grooves in tight electrical contact with said casing; an electrode disposed within said casing; insulating material interposed between said casing and said core on the one hand and said electrode on the other hand; and connections connecting said core and said electrode to the secondary terminals of said transformer. 75

6. An ozone machine comprising: a casing, acting as an electrode; a transformer located in said casing with one side thereof slightly spaced from the corresponding wall of said casing; a flat tube of insulating material interposed between said side and said wall and open at its ends to permit the passage of a current of air therethrough; an electrode disposed in said tube; and connections connecting said casing and said electrode to the secondary terminals of said transformer. 80

7. An ozone machine comprising: a casing, acting as an electrode; a transformer located in said casing with one side thereof slightly spaced from the corresponding wall of said casing, and with its core tightly in electrical contact with said casing; a flat tube of insulating material interposed between said side and said wall and open at its ends to permit the passage of a current of air therethrough; an electrode disposed in said tube; and connections connecting said core and said electrode to the secondary terminals of said transformer. 95

8. An ozone machine comprising: a casing, acting as an electrode; a transformer located in said casing with its core tightly in electrical contact with two opposite walls of said casing and with one side thereof slightly spaced from another wall of said casing; a flat tube of insulating material interposed between said side and said other wall and open at its ends to permit the passage of a current of air therethrough; an electrode disposed in said tube; and connections connecting said core and said electrode to the secondary terminals of said transformer. 100

9. An ozone machine comprising: a casing, having longitudinal grooves on the interior of two opposite walls, and acting as an electrode; a transformer located in said casing, having the two edges of its core tightly received within said grooves in tight electrical contact with said casing, and having one side thereof slightly spaced from another wall of said casing; a flat tube of insulating material interposed between said side and said other 115

wall and open at its ends to permit the passage of a current of air therethrough; an electrode disposed in said tube; and connections connecting said core and said electrode to the secondary terminals of said transformer.

10. An ozone machine comprising: a transformer, a flat tube of insulating material, and a flat electrode, all interconnectable to provide a compact assembly of ozonizer parts;

10 a casing, having opposed interior grooves, and a side wall spaced a predetermined distance from said grooves; said ozonizer assembly being insertable into said casing as a unit, the transformer disposed and held by

15 said grooves, and the remaining portions of said assembly being interposed in the space between said transformer and said side wall.

11. An ozone machine comprising: a transformer, a flat tube of insulating material, and

20 a flat electrode, all interconnectable to provide a compact assembly of ozonizer parts; a casing, having opposed interior grooves, and a side wall spaced a predetermined distance from said grooves; said ozonizer assembly

25 being insertable into said casing as a unit, the transformer disposed and held by said grooves, and the remaining portions of said assembly being interposed in the space between said transformer and said side wall,

30 and cooperating with said side wall to provide mechanism operable to generate ozone.

12. An ozone generator comprising a metal casing, a transformer supported in the casing, a relatively flat insulating tube between

35 the transformer and one wall of the casing, a substantially flat elongated electrode in said tube lying alongside said wall of the casing, the transformer having its terminals connected one to said casing and one to said elec-

40 trode.

13. In an ozone generator, a casing, opposite side walls thereof having outwardly extending grooves, a transformer, a core therefor having side members projecting laterally

45 beyond the coils of the transformer and slidably mounted in said grooves, an electrode, a dielectric element associated with said electrode and movable with said transformer into and out of said casing through one end there-

50 of, and closures for the ends of said casing.

In testimony whereof I hereunto affix my signature.

ALBERT E. EVANS.
